(57) **CLAIM**

The ornamental design for a motor housing for wheeled frame with motor, as shown and described.

DESCRIPTION

Cross reference is made to copending U.S. design patent application Ser. No. 29/683,827 entitled "Wheeled Frame with Motor" by Kindler et al., which was filed on even date herewith; U.S. design patent application Ser. No. 29/683,831 entitled "Wheeled Frame with Motor" by Kindler et al., which was filed on even date herewith; U.S. design patent application Ser. No. 29/683,832 entitled "Battery for Wheeled Frame with Motor" by Kindler et al., which was filed on even date herewith; U.S. design patent application Ser. No. 29/683,838 entitled "Wheeled Frame with Motor" by Gruber et al., which was filed on even date herewith; and U.S. design patent application Ser. No. 29/683,840 entitled "Wheeled Frame with Motor" by Gruber et al., which was filed on even date herewith.

FIG. 1 is a first perspective view of a motor housing for wheeled frame with motor showing our new design;

FIG. 2 is a second perspective view of the motor housing for wheeled frame with motor of FIG. 1;

FIG. 3 is a left side elevational view of the motor housing for wheeled frame with motor of FIG. 1;

FIG. 4 is a right side elevational view of the motor housing for wheeled frame with motor of FIG. 1;

FIG. 5 is a front side elevational view of the motor housing for wheeled frame with motor of FIG. 1;

FIG. 6 is a rear side elevational view of the motor housing for wheeled frame with motor of FIG. 1;

FIG. 7 is a top plan view of the motor housing for wheeled frame with motor of FIG. 1; and,

FIG. 8 is a bottom plan view of the motor housing for wheeled frame with motor of FIG. 1.

The broken lines shown in the drawings illustrate portions of the motor housing for wheeled frame with motor that form no part of the claimed design.
